UNITED STATES PATENT OFFICE.

CHARLES McCLINTOCK, OF ELWOOD, INDIANA.

COMPOUND TWITCH-HALTER.

No. 843,689.

Specification of Letters Patent.

Patented Feb. 12, 1907.

Application filed April 25, 1906. Serial No. 313,642.

To all whom it may concern:

Be it known that I, CHARLES McCLINTOCK, a citizen of the United States, residing at Elwood, in the county of Madison and State of Indiana, have invented certain new and useful Improvements in Compound Twitch-Halters, of which the following is a specification.

This invention relates to controlling devices for fractious or vicious animals, and has special reference to a novel type of halter that may be properly characterized as a "compound twitch-halter," the same being intended as an improvement upon the construction of halter disclosed in my companion application, Serial No. 303,569, filed February 28, 1906.

The primary purpose of the present invention is to provide a controlling or twitch halter having a compound action—that is, embodying a double twitch-noose which secures a compound twitching effect and renders it much easier to control a vicious animal than through the employment of a twitch having but a single noose. The latter construction performs its functions effectually in ordinary cases; but in strong and powerful animals of an exceedingly vicious or fractious nature it is necessary to provide a construction of twitch sufficiently powerful in its twitching effect to place the animal under thorough subjection. It is for this purpose that the present invention is designed, and the same also involves as another improvement an improved construction of pulley-block of a duplex form and embodying a rope-lock for fastening the twitch after having been once tightened about the animal's throat and gums.

With these and many other objects in view, which will more readily appear as the nature of the invention is better understood, the same consists in the novel construction and arrangement of parts hereinafter more fully described, illustrated, and claimed.

The essential features of the invention involved in carrying out the improvements above referred to are susceptible to structural modification without departing from the scope of the invention; but a preferred construction is shown in the accompanying drawings, in which—

Figure 1 is a perspective view of the improved compound twitch-halter shown in its applied position upon the head of a horse. Fig. 2 is a perspective view of a halter re-

moved from the animal and showing the various parts thereof in their relative operative position. Fig. 3 is a detail in perspective of a preferred form of duplex pulley-block form- 60 ing a part of the halter.

The invention includes two principal elements—viz., a single-length halter-rope 1 and an antifriction-guide, (designated in its entirety by the numeral 2). 65

In carrying out the special objects contemplated by the present invention the antifriction-guide 2 preferably consists of a duplex pulley-block provided with a hanger-eye 3 and at one side of the plane of the latter with 70 a pair of housings 4, accommodating therein the separate guiding pulleys or sheaves 5, which are designed to respectively receive thereover separate runs of the halter-rope 1, as will be presently explained. Also a distinctive feature of the invention resides in 75 associating with the duplex pulley-block or antifriction-guide 2 a rope-lock for the pull portion of the rope. This rope-lock preferably consists of a wedge-shaped key 6, inserted in one of the housings 4 above the pulley or sheave 5 therein and provided at the small end with a shouldered stop 7, which prevents displacement thereof in one direction, while displacement in the other direction is prevented by the enlarged head portion 8 of the key. 85

In adapting the halter-rope to the animal's head the same is first strung through the hanger-eye 3, and at the point where the 90 intermediate portion of the rope engages said eye the same is formed with an intermediate single slip-knot 9. This slip-knot before being closed onto the hanger-eye 3 is designed to receive thereover one of the 95 terminals of the rope which is provided with the knotted head 10, which when the knot 9 is closed and tightened is held fast therein. Before closing the loop 9 the knotted end portion 10 of the rope is passed around the animal's neck, so that the duplex pulley-block 100 2 will be suspended directly beneath the throat of the animal. From the slip-knot 9 the rope is passed upon both sides or cheeks of the animal's head to form a primary 105 twitch-noose 11, which is passed around the upper gum of the animal, and the upper lip is pushed up to admit of such positioning of the noose. The run of the primary twitch-noose 11 opposite the run reaching from the 110 knot 9 is passed about one of the pulleys 5 and around the sides or cheeks of the ani-

mal's head to form another and second twitch-noose 12, which is likewise passed around the upper gum of the animal's mouth, and the free end or pull portion of the rope is passed about the second guiding pulley or sheave 5 beneath the rope lock or key 6.

With the parts in the positions described, and shown in Fig. 2 of the drawings a pull upon the free end of the halter-rope will

- 10 tighten both of the nooses 11 and 12 and serve to twitch the upper gum of the animal with a powerful grip, with the result of placing the animal under immediate subjection. When the rope has been tightened sufficiently by the pull on the free end thereof, the wedge or binding key 6 is tightened upon the portion of the rope therebeneath by simply pressing such key in a longitudinal direction to effect the gripping action; but
- 15 20 when it is desired to loosen up the halter it is simply necessary to press upon the key or lock from the opposite end, with the result of loosening up the rope, so that pressure can be removed from the animal's gum.
- 25 30 To remove the device, it is simply necessary to loosen up the single slip-knot 9 and pull out the knotted terminal 10 of the neck-engaging loop 12.

From the foregoing it is thought that the construction and action of the herein-described twitch will be readily understood without further description.

I claim—

- 1. A twitch-halter of the class described consisting of a single-length halter-rope arranged to form a neck and throat engaging loop, and a pair of twitch-nooses extending from said loop and adapted to engage about the upper gum of the animal, and a guide 40 arranged to receive the runs of the rope forming the two nooses.

2. A twitch-halter of the class described consisting of a single-length halter-rope arranged to form a neck and throat engaging loop, and a pair of duplicate twitch-nooses 45 extending forwardly from the loop and adapted to engage about the upper gum of the animal, and a guide supported on the neck and throat engaging loop and receiving the runs of the rope forming the two nooses. 50

3. A twitch-halter comprising a duplex pulley-block adapted to be arranged at the animal's throat and provided with a pair of guiding-pulleys, and a rope-locking wedge loosely mounted in one of the housings above 55 the pulley therein, and a single-length halter-rope reeved about the pulleys of the block to form a pair of twitch-nooses adapted to extend about the animal's head and engage the upper gum of the mouth, the free end portion 60 of the rope passing beneath said locking-wedge, and one portion of the rope having a fast connection with the pulley-block and extended into a neck and throat engaging loop.

4. A twitch-halter consisting of a single-length halter-rope arranged to form a neck and throat engaging loop, and a twitch-noose extending from said loop and adapted to engage about the upper gum of the animal, and a pulley-block arranged at the animal's throat and having a pulley receiving the free portion of the rope, and a rope-locking wedge loosely mounted in the housing above said pulley. 70

In testimony whereof I hereunto affix my signature in the presence of two witnesses.

CHARLES McCLINTOCK.
